[57] CLAIM

The ornamental design for an interior of a truck door panel, as shown and described.

DESCRIPTION

FIG. 1 is a perspective view of an interior of a truck door panel showing our new design;

FIG. 2 is a front view of the embodiment of the invention shown in FIG. 1;

FIG. 3 is a rear view of the embodiment of the invention shown in FIG. 1;

FIG. 4 is a top view of the embodiment of the invention shown in FIG. 1;

FIG. 5 is a side view of the embodiment of the invention shown in FIG. 1; and,

FIG. 6 is a bottom view of the embodiment of the invention shown in FIG. 1.
